UNITED STATES PATENT OFFICE.

ARTHUR E. KENNELLY, OF ORANGE, ASSIGNOR TO THOMAS A. EDISON, OF
LLEWELLYN PARK, NEW JERSEY.

ELECTRICAL INDICATOR.

SPECIFICATION forming part of Letters Patent No. 517,163, dated March 27, 1894.

Application filed October 26, 1892. Serial No. 450,063. (No model.)

To all whom it may concern:

Be it known that I, ARTHUR E. KENNELLY, a subject of the Queen of Great Britain, residing at Orange, in the county of Essex and State of New Jersey, have invented a certain new and useful Improvement in Electrical Indicators, of which the following is a specification.

The present invention relates to electrical measuring or indicating devices of that class employing a magnet of constant strength, between the poles of which is a pivoted armature controlling a pointer movable over a graduated scale.

15 The main object of the invention is to improve the construction of instruments of the character indicated, whereby increased simplicity and more perfect operation are secured, and the invention consists in the several features and combinations hereinafter more fully described and specifically set forth in the claims.

In the accompanying drawings illustrating the invention, Figure 1 is a plan view of the instrument with its cover removed. Fig. 2 is 25 a section on line $x-x$ of Fig. 1, looking in the direction of the arrow. Fig. 3 is a detail view illustrating the construction and winding of the armature, (which winding is omitted in Fig. 2 to avoid confusion of lines;) and Fig. 4 shows a modification.

The permanent magnet 1, preferably employed, is of horseshoe or curved form, having ends nearly meeting at one side as shown 35 in Fig. 1. To the ends of this permanent magnet are secured wrought iron pole pieces 2, 3, by means of screws 4. These pole pieces preferably terminate in rounded ends 5, which ends are considerably thinner than the main 40 portion of the pole pieces, as shown in Fig. 2. Each pole piece is preferably cut away at 6 to make room for the spindle and hub of the armature, as most clearly shown in Fig. 2.

7 is a non-magnetic bar secured to the permanent magnet and forming a support for the plate 8 which supports the bearing 9 for the spindle 10 and the insulated plate 11, which carries an arm 12, to which a light coil spring 13 is connected, the opposite end of said coil 50 being connected to the spindle in such manner as to tend to turn the pointer 14 to zero.

13' is a second spring co-operating with the first and supported, in the manner indicated in the drawings, so as to be insulated from the spindle.

55

15 is a small counterbalance weight.

The armature is a thin disk armature, and preferably consists of an aluminium disk 16, to the periphery of which is secured a rubber ring 17, having a groove around it, and having notches 18 at intervals on one side, and at one point having a wider notch 19 to receive the wire of the armature winding as hereinafter described. At the center the disk 16 is stamped into cup form, forming a hub 65 20 which rests on the sleeve 21 on the spindle.

The preferred mode of winding the disk armature is indicated in Fig. 3. Starting from the point 22 an insulated wire is led radially across the upper face of the aluminium disk, being bent down into, and around the center of, the hub 20, then radially along the surface of the plate to the diametrical notch 18, then around toward the right in the groove of the ring to the notch 19, then again 75 across the face of the disk to said notch 18, then around in the groove of the ring toward the left, thus giving a differential winding on the periphery; the winding then extends to the next notch 18, and so on until there are 80 radial wires extending to each of the notches around the periphery of the ring. The end 22 is connected to the spindle and thence to the plate 11, as indicated in Fig. 2, while the other end 23 is connected to the spring 13', 85

+, - are the line terminals of the instrument and are connected by means of a wire 25 including a resistance 26, which is, for convenience, wound directly on the body of the 90 permanent magnet. From the same terminal a wire 27 extends to the insulated plate 11, thence through the armature coil and wire 23 to spring 13', thence to 23', to the - terminal, thus completing the circuit of the 95 instrument. The armature winding described gives a considerable number of wires extending from the notch 19 to the center of the disk, and in order that the armature may be perfectly balanced, the counterbalance 15 is 100 placed opposite to said notch. This collection of wires on the armature surface is so located

as to be outside of the magnetic field between the facing, overlapping, magnet poles, and preferably normally stands directly in line with the pointer 14 as indicated in Fig. 1. By 5 bending the wire down into the hub 20 as described it is held in place without special fastenings, and without forming a thick portion which might interfere with the movement of the armature in its thin field between the magnet 10 net poles. It will thus be seen that the winding consists of a series of radii in all of which the current flows either to or from the center. Supposing the latter case, the arrangement approximates to a plane current sheet spreading 15 uniformly from center to edge of the disk, except at the radial portion 19 which is never allowed to enter the field, and which allows the current turns to pass back from the edge to the center of the disk. Since the two opposite 20 polar faces are semi-circular, they can only cover one half of the surface of the disk, and the radial section 19 occupies some position in the unoccupied semicircle. When current is supplied to the disk winding, all the radii 25 between the poles will aid in setting up a rotatory couple tending to move the disk round its axis either to the right or left. As the disk turns, as many active wires enter the field at one side as leave it on the other, so 30 that the rotatory couple remains constant so long as the notch 19 does not approach the field too closely. Of the half revolution that is ideally permissible to give the disk without bringing the notch 19 between the poles, 35 it is practically convenient to utilize one hundred and twenty or one hundred and thirty degrees, and with this arrangement the distance between the section 19 and the pole faces is never so small as to seriously affect 40 the uniformity of the rotatory couple. The active wires carried round the periphery of the disk, as for example from the notch marked 18 in Fig. 4 to that marked 19, are all 45 outside the circle of the pole faces, and by carrying the wires round in alternately opposite directions, any stray field passing them exerts no appreciable resultant magnetic influence. When the circuit of the instrument is closed, the armature will give a steady, uniform 50 pull, depending on the current on the line, for all positions, so that the scale 28 can be divided into divisions of regular length and calibrated by a single trial. Owing to the form of the armature, the poles of the 55 magnet can be quite large and can be brought very close together, thereby largely reducing the magnetic resistance of the air gap, and making the operation of the instrument much more efficient and regular than with any other 60 form of armature, and the armature pointer can be mounted so as to be capable of movement through a longer arc than heretofore practicable.

In practice the scale can be made one hundred and twenty degrees or more, thereby 65 making it possible to use large divisions on

the scale. When the circuit through the instrument is broken, the pointer will gradually be returned to zero by means of the springs 13, 13'. The instrument will be dead-beat, since 70 currents will be generated in the metal disk, forming the body of the armature, tending to oppose sudden movements thereof. The armature described gives a continuous rotary effect with no other appreciable component, 75 such as a side strain on its bearing, and hence the instrument gives very perfect results.

In setting up the instrument, the armature is put in position before the pole piece 2 is secured to the magnet. Said pole piece is 80 then put in place, and the steel magnet magnetized by means of a suitable coil or otherwise.

While the instrument has been above described in relation to its use as an ammeter, 85 it can obviously be used as a volt meter. This would generally require the use of a resistance coil in the main circuit, and preferably the omission of the shunt. The winding of the armature can also be varied to 90 some extent. There need not necessarily be two wires in each armature notch, although there will be two or more when the winding has many turns. The differential condition will not be materially affected if one wire 95 only be led to each notch, as shown in Fig. 4, provided that the returns to the entrance notch 19 are successively carried in opposite directions. It may not always be desirable to enter the first radial wire on the disk exactly opposite to the large notch 19, as the differential arrangement will generally be more effectively carried out by commencing at some other radius, as indicated at r Fig. 4. This is for the reason that the differential 100 balance cannot be perfect everywhere around the periphery, and it is desirable to make it 105 strictly correct for full load.

What I claim is—

1. The combination, in an electrical indicator, of a magnet, a disk armature situated flatwise between the poles of said magnet and having a winding adapted to carry the current to be measured, and an indicating device moved by said disk armature, substantially as described.

2. The combination, in an electrical indicator, of a permanent magnet having extended pole pieces facing each other in close proximity, a disk armature situated flatwise in the narrow space between said pole pieces, the coil or winding of such armature being connected to the terminals of the meter and adapted to carry the current to be measured, and an indicating device moved by said disk armature, substantially as described.

3. The combination, in an electrical indicator, of a horseshoe or approximately circular magnet having overlapping pole pieces, an armature situated flatwise in the space between the overlapping pole pieces, said armature having a coil adapted to carry the cur-

rent to be measured, and an indicating device movable with the armature, substantially as described.

4. The combination, in an electrical indicator, of a magnet having facing pole pieces, an armature consisting of a non-magnetic disk and a coil extending radially across the face of the disk and around the periphery thereof alternately in opposite directions in the manner described, and connected to terminals of the meter.

5. An armature consisting of a suitable disk or body, and a winding extending radially across the same and around the edge in one direction, then again across the same and around the edge in the opposite direction, and so on until the winding is complete, substantially as described.

6. An armature consisting of a non-magnetic disk, a ring around the periphery of the same, and a winding extending across the face of the disk and around the ring alternately in opposite directions in the manner described.

7. The combination, in an armature, of the disk 16, the insulating ring 17 with notches 25 at intervals, and the winding crossing the face of the disk and extending around the same from the notches alternately in opposite directions as described.

8. The combination with the magnet, of the disk armature situated flatwise between the poles of said magnet and having a winding extending radially from center to periphery, then round the periphery to a common radial sector over which return is made to the center, the said sector of return being so situated as never to enter the magnetic field within the range of the disk's motion, substantially as set forth.

This specification signed and witnessed this 17th day of October, 1892.

A. E. KENNELLY.
